UNITED STATES PATENT OFFICE.

WILLIAM H. ALCORN, OF PORTSMOUTH, OHIO.

RETORT.

Application filed June 20, 1923. Serial No. 646,659.

To all whom it may concern:

Be it known that I, WILLIAM H. ALCORN, a citizen of the United States, residing at Portsmouth, in the county of Scioto and 5 State of Ohio, have invented a new and useful Retort, of which the following is a specification.

This invention relates to a retort designed for use wherever a reduction process is involved although the retort is primarily designed for use in the extraction of oil from shale.

One of the objects of the invention is to provide an apparatus through which shale 15 or the like can flow continuously, the same being thoroughly agitated and heated during its passage through the apparatus so as to act efficiently to separate the oil from the shale.

20 Another object is to provide a structure wherein hot products of combustion as well as steam jackets can be used for the purpose of maintaining high temperature in the retort unit.

25 A further object is to provide a structure outside of the walls of the retort for supporting the bearings of the rotatable part so that they will not be displaced or otherwise affected by expansion or contraction of

30 the walls of the retort.

With the foregoing and other objects in view which will appear as the description proceeds, the invention resides in the combination and arrangement of parts and in 35 the details of construction hereinafter described and claimed, it being understood that changes in the precise embodiment of the invention herein disclosed may be made within the scope of what is claimed without 40 departing from the spirit of the invention.

In the accompanying drawings the preferred form of the invention has been shown.

In said drawings

45 Figure 1 is a central vertical longitudinal section through the apparatus.

Fig. 2 is a section on the line 2—2, Fig. 1.

Fig. 3 is a section on the line 3—3, Fig. 2.

Fig. 4 is a section on the line 4—4, Fig. 1.

Referring to the figures by characters of 50 reference 1 designates the brick walls of the retort housing a furnace portion 2 and a series of superposed retort units. Each of these units includes a cylinder 3 the ends of which are fixedly mounted in the walls. 55 Those portions of the cylinders arranged within the retort are surrounded by casings

4 forming steam jackets. The steam jackets abut against opposed walls of the retort and are concentric with and completely surround the cylinders. The several steam 60 jackets are connected in series by pipes 5, steam being admitted to the lower jacket by pipes 6 and being exhausted from the upper jacket by a pipe 7.

Each of the cylinders 3 has a central bearing 8 projecting outwardly from each end at the center and journaled in these bearings are shafts 9 suitably packed as shown at 10. The ends of the shafts are mounted for rotation in bearings 11 carried by a 65 structural steel frame 12. Sprockets 13 are carried by the shafts and are engaged by chains 14 whereby all of the shafts can be rotated simultaneously.

Opening into one end portion of the upper 70 cylinder 3 is a steam pipe or chute adapted to be connected to the bottom of a hopper or the like containing crushed shale. This pipe or chute 15 has a rotary valve 16 75 therein for controlling the flow of material into the upper cylinder. The valve can be rotated by any suitable mechanism provided for that purpose, the said valve being carried by a shaft 17 that projects laterally 80 beyond the retort wall.

Secured to each of the shafts 9 within the cylinders 3 is a series of agitating blades 18. Each of these blades has its end portions twisted as shown particularly in Figs. 1 and 2, the blades being so shaped and assembled that the material dropped into one end of a cylinder will be propelled by the rotating blades toward the other end of the cylinder. Each blade 18 has a central transverse recess 19 for the reception of a portion of 95 the shaft 9, that portion of the shaft engaged by the blades being preferably angular in cross section as shown in Fig. 2. U-bolts straddle the shafts and are secured in the blades so as to hold them tightly 100 to the shafts. These bolts 20 can be tightened readily and can be adjusted along the shafts so as to secure the blades thereto at the desired distances apart.

Arranged adjacent to one wall of the 105 retort is a header or condensing pipe 21 and this pipe communicates with the respective cylinders 3 through pipes 22. These pipes extend from the upper portions of the cylinders at one end thereof where vapors generated within the cylinders can flow freely 110 into the pipes.

Stacks 23 extend upwardly from and open through the shafts of the retort structure and have dampers 24 for controlling the flow of gases. Hot products of combustion are 5 adapted to leave the retort by way of the stacks after circulating around and between the jackets 4 on the cylinders 3.

Extending downwardly from that end of the uppermost cylinder farthest removed 10 from the chute 15 is a delivering port 25 that opens downwardly into the top portion of the next cylinder thereunder. This second cylinder is provided in the lower portion thereof at its other end with an outlet port 26 opening downwardly into the top of the next adjoining cylinder. A port 27 connects the two lower cylinders at one end and an outlet chute 28 projects downwardly from one end of the lower cylinder 20 as shown. The ports within opposed walls of the retort serve to maintain communication between adjoining cylinders, as will be obvious.

After the shafts have been set in motion, 25 and fuel has been ignited in the furnace portion 2 of the retort, the material to be treated is allowed to flow through the chute 15 into the upper cylinder 3. It will be forced by the rotating blades 18 toward the 30 other end of said cylinder where it will gravitate into the second cylinder. The blades in this second cylinder will direct the material toward the other end thereof. There the material will flow downwardly 35 through port 26. This travel of the material back and forth through the cylinders will continue until the lowermost cylinder is reached at which time the residue is delivered through the chute 28. While passing 40 through the cylinders the material is subjected to an intense heat from the ignited fuel, and also from the steam jackets

4. This heat is sufficient to drive hydro-carbon oils from the shale or other material being treated so that they will pass outwardly through the pipes 22 and into the pipe 21. 45

Pipe 21 can be provided with a water jacket 29 having inlet and outlet pipes 30 so that the vaporized by-products delivered 50 in the pipe 21 will be condensed and can then be drawn off from the bottom of said pipe.

What is claimed is:—

In a retort the combination with masonry 55 walls forming a furnace structure, of stationary superposed cylinders extending through opposed walls and across the interior of the retort, ports within opposed walls of the retort for maintaining communication between adjoining cylinders, the inlet and outlet of each cylinder being located adjacent the respective ends of the cylinder, said inlets and outlets being formed by the respective ports, steam jackets abutting 60 against opposed walls of the retort and concentric with and completely surrounding the cylinders, a steam pipe connecting the jackets, propelling blades mounted for rotation within each of the cylinders, means for 65 simultaneously rotating the blades for forcing material in the cylinders from the inlet to the outlet ports, a fuel supporting grate in the lower portion of the retort below all of the steam jackets, a condensing header, 70 a water jacket thereon, and pipes connecting the condenser with one end of each of the cylinders, all of the steam jackets being exposed to heat generated within the retort. 75

In testimony that I claim the foregoing 80 as my own, I have hereto affixed my signature.

WILLIAM H. ALCORN.
